 Acme Steel Company, Chicago, Ill., a corpora-
 tion of Illinois

Application November 7, 1932, Serial No. 641,568

7 Claims. (Cl. 217—89)

This invention relates to containers of a type adapted for use as candy pails, butter tubs and the like and its purpose is to provide a uniform construction and a new method of manufacture adapted to overcome numerous difficulties which have heretofore been met in the manufacture and use of containers. It is frequently necessary to remove the covers of candy pails, butter tubs and the like for the purpose of inspecting the 10 contents, after which the covers must be replaced until the contents of the containers are ready for use, and this requires a form of construction which will permit of removal of the covers without injury thereto or to the means by which they are secured in place. Most fastening devices for pail covers have heretofore been of a type which required their destruction or deformation in removing the cover and it has been impossible to replace covers with the same security that 20 they possessed at the time that the containers were originally packed. The principal object of the present invention is to provide a new form of container having an annular rim adapted to interlock with the cover and having parts capable of relative movement with respect to the body portion of the rim to permit the cover to be removed and restored when desired. A further object of the invention is to provide an improved container comprising an integral rim having 30 parts adapted to be deformed to project over the cover to hold it in place. Still another object of the invention is to provide an improved method of forming a container according to which an annular metallic rim is interlocked with 35 the upper portion of the vessel and provided with an upwardly projecting part having longitudinal slits therein which permit the upper edge portions thereof to be bent inwardly to overlie the top surface of the cover. A further object 40 of the invention is to provide an improved form of container comprising a vessel having an annular groove adjacent its upper edge in combination with an annular metallic rim having an inwardly projecting flange along its lower edge to engage said groove and an annular bead along its upper edge, with longitudinal slits at 45 intervals beneath said bead, whereby portions of said bead may be bent inwardly to overlie a cover seated on the upper end of said vessel. 50 Other objects relate to various features of construction and arrangement which will appear more fully hereinafter.

The nature of the invention will be understood from the following specification taken 55 with the accompanying drawings in which one

form of the improved container is illustrated in connection with one method of forming it.

In the drawings,

Fig. 1 is a perspective view of the improved container of the present invention with a part 60 thereof broken away;

Fig. 2 is a top plan view of a portion of the container illustrated in Fig. 1 showing, on an enlarged scale, one of the parts of the rim which is bent inwardly to overlie the cover; 65

Fig. 3 shows a side elevation of the portion of the container illustrated in Fig. 2;

Fig. 4 shows a partial vertical section through one side portion of the container illustrated in Fig. 1 with the cover thereof in the position 70 which it occupies before being passed downwardly within the annular rim;

Fig. 5 is a partial vertical section similar to that of Fig. 4 showing the relative positions of the parts after the cover has been put in place 75 on the upper edge of the vessel within the rim and after portions of the rim have been bent inwardly to overlie the cover;

Fig. 6 shows a perspective view of a portion of the sheet metal strip on which the annular 80 metallic rim is formed;

Fig. 7 is a perspective view of a portion of the annular metallic rim which is formed on the sheet metal blank illustrated in Fig. 6; and

Fig. 8 is a perspective view of the end portions 85 of the annular metallic rim before these parts have been overlapped and united with each other.

As illustrated in the drawings, the invention comprises a vessel 10 having an annular wall 90 11 which may be flared upwardly from its lower edge and which is formed preferably of wood or wood veneer. The ring 12, formed of wood or other suitable material, is secured around the inside of the wall 11 adjacent its lower edge 95 and this ring forms a ledge on which is seated the circular bottom wall 13 of the vessel. Around the upper edge of the vessel 10, there is secured an annular metallic rim 14 which is adapted to secure in place the circular cover 100 15 which may preferably be formed of wood or wood veneer and which has an annular flange 15^a adapted to seat upon the top edge surface 11^a of the annular wall 11 with the annular shoulder 15^b of the cover extending downwardly 105 within the wall of the vessel, as shown in Fig. 5.

The annular wall 11 of the vessel is provided on its outer side, and near its upper edge, with an annular inwardly extending groove 11^b which is adapted to be engaged by an annular flange 110

14^b formed along the lower edge of the rim and preferably united with the body portion 14^a of the rim by means of an annular outwardly extending bead 14^c which is provided primarily for the purpose of adding strength to the rim so that it may more effectively hold the annular wall 11 in such shape that it has a true circular cross section. The body portion 14^a of the metallic rim is flared upwardly to a slight extent 10 to correspond with the flare of the wall 11. This flare may be imparted to the rim by driving it on to the vessel 10 from the bottom thereof until the flange 14^b snaps into engagement with the groove 11^b, with the result that the rim is flared to fit closely against the wall of the vessel. When the rim reaches this final position 15 on the vessel, it projects above the top edge surface 11^a of the vessel and this projecting portion is adapted to receive within it the circular cover 15.

The rim 14 is provided around its upper edge with an annular outwardly turned bead 14^d which is preferably a complete bead having a substantially circular cross section. At intervals 20 around the circumference of the rim 14 the body portion 14^a thereof is provided with longitudinal slits 14^e which are located just beneath the lower margin of the bead 14^d and in a plane just above the upper surface of the cover 15 when the cover is seated on the vessel as shown in Fig. 5. After the cover has been moved downwardly within the rim 14 from the position shown in Fig. 4 to the position shown in Fig. 5, the portions of the bead 14^d which lie above 25 the slits 14^e are bent inwardly to form projections 14^f which overlie, and preferably contact with, the upper surface of the cover 15 so that they securely hold the cover in place on the vessel. It will be apparent that these projections 14^f may be bent inwardly by a pair of pliers or any other conventional tool and that, when the contents of the vessel are to be inspected, these projections may be bent outwardly to permit the removal of the cover, after 30 which the cover may be restored and the parts of the rim above the slots again pushed inwardly to hold the cover in place.

The rim 14 is preferably formed from an elongated strip 14^g of steel or the like which is 35 comparatively hard and stiff although having sufficient ductility to permit the formation of the beads 14^c and 14^d. This strip is run through suitable rolls or the like which form the beads 14^c and 14^d thereon while at the same time forming the flange 14^b which projects inwardly beyond the inner surface of the body portion 14^a of the resulting rim. The slits 14^e may also be formed by suitable shearing blades or the like 40 which operate as the strip 14^g passes between the rolls. The elongated metal strip having the beads and flange formed thereon is then cut off in suitable lengths to form the annular rim 14 and the end portions of each length are then 45 cut away along their upper and lower edges, as shown in Fig. 8, to form projecting tongues 14^h which are adapted to overlap the body portions 14^a of the rim when the ends of the beads are brought together, as illustrated in Fig. 1. The overlapping end portions of the rim may then 50 be secured together by means of spot welds or rivets 16. The annular rim is then formed and

is in readiness to be applied to the vessel 10. Although one form of the improved container and one method of constructing it have been shown and described by way of illustration, it will be understood that the invention may be constructed in various forms and that the improved method may be practiced in various ways within the scope of the appended claims.

I claim:

1. The combination in a container, of a vessel, a rim surrounding the upper part of said vessel and having longitudinal slits therein, and a cover seated on said vessel, said rim having parts above said slits bent inwardly over said cover. 85

2. The combination in a container, of a vessel, a rim surrounding the upper part of said vessel and having a bead along its upper edge, said rim having longitudinal slits therein beneath said bead, and a cover seated on said vessel, portions of said bead above said slits being bent inwardly over said cover. 95

3. The combination in a container, of a vessel, a metallic rim surrounding the upper part of said vessel and having a plurality of annular beads formed thereon, said rim having longitudinal slits therein adjacent one of said beads, and a cover for said vessel, said rim having parts of one of said beads adjacent said slits bent inwardly over said cover. 100

4. The combination in a container, of a vessel, a cover having a part fitting within said vessel and having an annular flange extending over the upper edge thereof, and a metallic rim secured to said vessel and having a part thereof extending upwardly beyond said cover, said rim having longitudinal slits therein adjacent the upper surface of said cover forming parts adapted to be bent inwardly over said cover. 110

5. The combination in a container, of a vessel having an annular groove in its outer surface, an annular metallic rim having an inwardly extending annular flange engaging said groove and having an annular bead around its upper edge, and a cover seated on said vessel within said rim, said rim having longitudinal slits therein beneath said bead to permit parts of said bead to be bent inwardly over said cover. 115

6. The combination in a container, of a vessel having an annular groove in its outer surface, an annular metallic rim having an inwardly extending annular flange engaging said groove and having an annular bead around its upper edge, and a cover seated on said vessel within said rim, said rim having longitudinal slits therein beneath said bead to permit parts of said bead to be bent inwardly over said cover, said rim having a second annular bead formed therein beneath said first named bead. 125

7. The combination in a container, of a vessel having an annular groove in its outer surface, an annular metallic rim having an annular bead along its lower edge terminating in an annular flange which projects into said groove, and a cover seated on said vessel within the upper part of said rim, said rim having longitudinal slits therein to permit parts thereof at its upper edge to be bent inwardly over said cover. 135

CHESTER M. MACCHESNEY.
